(57) **CLAIM**

The ornamental design for a side mirror for an automobile, as shown and described.

DESCRIPTION

FIG. 1 is a front elevational view of a side mirror for an automobile in accordance with my new design;
FIG. 2 is a top plan view thereof;
FIG. 3 is a left side elevational view thereof;
FIG. 4 is a right side elevational view thereof;
FIG. 5 is a first side perspective view thereof;
FIG. 6 is a second side perspective view thereof; and,
FIG. 7 is a rear elevational view thereof.

The inside surfaces of the side mirror, shown in broken lines in FIGS. 4 and 5, form no part of the claimed design since the inside surfaces are hidden when the side mirror is mounted to the automobile.

A second embodiment of our new design includes the mirror image of the side mirror shown in FIGS. 1 to 7.
